UNITED STATES PATENT OFFICE

HENRY W. SCHOENFELDT, OF YOUNGSTOWN, OHIO

PENCIL SHARPENER

Application filed August 6, 1930. Serial No. 473,401.

This invention relates to pencil sharpeners.

The most commonly used forms of pencil sharpeners require the use of both hands for 5 the manipulation of the same, the pencil being held by one hand and the cutters or cutter head being actuated by the other hand.

One important object of the present invention is to provide a novel form of pencil 10 sharpener wherein the hand holding the pencil is also used to manipulate the sharpening mechanism.

A second important object of the invention 15 is to provide an improved form of such mechanism which may be taken apart with ease for the purpose of sharpening or replacing the cutter plate used therein.

A third important object of the invention 20 is to provide a novel device of this character wherein simple depression of a plunger will operate a rotatable cutter head.

With the above and other objects in view, as will be presently understood, the invention 25 consists in general of certain novel features of construction and combinations of parts hereinafter fully described, illustrated in the accompanying drawings and specifically claimed.

In the accompanying drawings like characters of reference indicate like parts in the several views, and:

Figure 1 is a side elevation of one form 30 of the improved pencil sharpener.

Figure 2 is a section on the line 2—2 of 35 Figure 1.

Figure 3 is a section on the line 3—3 of Figure 2.

Figure 4 is a section on the line 4—4 of Figure 2.

Figure 5 is a view similar to Figure 2 40 but showing a modified form of the pencil sharpener.

Figure 6 is a section on the line 6—6 of Figure 5.

In both forms of the device there is provided a cylindrical casing body 10. The lower end of this body is closed by a closure plate 11 having a peripheral flange 12 which is provided with bayonet slots 13 cooperat- 50 ing with pins 14 projecting from the body

10 to hold this lower end in position. A felt or other suitable pad 15 may be secured to the closure plate 11 to prevent marring furniture on which the device is placed. Also in each of the forms there is provided a top 16 having a peripheral flange 17 screwed onto the upper end of the body 10. This top 16 has a central pencil receiving opening from which depends a guide tube 17'. Just below the lower end of the guide tube 17' 60 the body 10 is provided with inwardly projecting lugs 18 whereon rests a partition plate 19 held to the lugs by screws 20. This partition plate has a centrally disposed opening surrounded by a rabbet 21. The cutter head in each form has a body 22 provided adjacent its upper end with a flange 23 which bears against the lower face of the plate 19, the upper end of the body fitting in the opening of said plate. The upper end 70 of this body is likewise provided with a screw threaded socket for the reception of a tubular member 24 having a flange 25 which fits in the rabbet 21. By this means the cutter head is revolvably mounted in the plate 75 19 and is held from displacement with reference thereto. Projecting downwardly from the lower end of the head 22 is a shaft 26 which seats in a socket 27 positioned centrally of the plate 11 so that the cutter head 80 is supported for rotation both at its upper and lower ends. The upper part of the cutter head and the member 24 are provided with a cylindrical bore 28 forming a continuation of the bore of the tube 17. At the 85 lower end this bore is continued downward in a conical extension 29 and the cutter head, at this conical extension, is cut away as at 30 in Figure 4, to provide a flat surface against which may be positioned a knife 31 90 held in adjusted relation to the axis of the cutter head by screws 32 passing through slots 33. By means of this construction the knife may be adjusted in or out toward the axis or may be removed for sharpening or 95 replacement.

Extending downwardly through the shaft 26 is a passage 34 forked at its lower end to open outwardly through the sides of the shaft as at 35. This passage is to convey the scrap- 100

ings from the pencil lead downwardly to the bottom of the casing or receptacle.

In the form of the invention shown in Figures 1 to 4 there is provided on the upper part 5 of the cutter head a bevelled gear 36 wherewith meshes a bevelled pinion 38 fixed on a shaft 39 mounted in a bearing 40 depending from the plate 19. On the outer end of this shaft is fixed a spur pinion 41 wherewith 10 meshes a vertical rack 42 passing upwardly through a guide 43 on the plate 19 and through a guide 44 on the top 16. The rack 42 is continued upwardly in a rod 45 terminating at its top in a head 46. Projecting 15 upwardly from the lower plate 11 is a small tube or guide 47 and projecting downwardly from the lower end of the rack 42 is a stem 48 which slides in this guide, a spring 49 surrounding the tube 47 and stem 48 and normally holding the plunger formed by the rack and rod 45 with its head 46, in a raised position. A guard tube 50 surrounds the spring and lower parts of the plunger to prevent 20 clogging by the chips and dust which collect 25 in the lower part of the casing because of the operation of the device.

In the form of the invention shown in Figures 5 and 6 the cutter head carries a worm or spur gear 51 wherewith meshes a multiple 30 threaded worm 52 sliding through a guide 53 on the plate 19. This worm 52 has a rectangular opening therein which receives a rectangular guide bar 54 projecting up from the bottom plate 11 so that the worm 52 may move 35 vertically but cannot rotate. A spring 55 surrounds the bar 54 and normally holds the worm raised. A guard sleeve or tube 56 surrounds the spring and is of sufficient size to permit worm 52 to descend therein, this 40 sleeve 56 serving to prevent the chips and dust from interfering with the spring. A stem 57 extends upwardly through a guide 58 on the top plate and terminates in a head 59.

In the operation of either form of the device 45 the pencil is grasped in the fingers of one hand and inserted in the tube 17, the hand resting on the head 46 or 59 as the case may be. As the pencil is pushed down into the conical bore 29 the plunger is likewise pushed 50 down and through its geared connection to the cutter head causes the latter to rotate and thus sharpen the pencil. It is obvious that it may be necessary to make several up and down movements of the plunger, especially 55 with a pencil which has never before been sharpened but in all instances the same hand that operates the plunger holds the pencil.

There has thus been provided a simple and 60 efficient device of the kind described and for the purpose specified.

It is obvious that minor changes may be made in the form and construction of the invention without departing from the material spirit thereof. It is not, therefore, desired 65

to confine the invention to the exact form herein shown and described, but it is desired to include all such as properly come within the scope claimed.

Having thus described the invention, what 70 is claimed as new, is:

1. In a pencil sharpener, a casing, a partition plate spaced below the top of the casing and having a central opening therein, a cutter head having its upper end fitting revolubly in said opening, a flange on said cutter head below the plate and bearing on the under side thereof, a securing member screwed in said head and bearing against the upper side of the plate, a plunger extending 75 from said casing parallel to the axis of and adjacent said cutter head, and gearing connecting the plunger and cutter head to rotate the latter upon depression of the plunger. 80

2. In a pencil sharpener, a casing, a partition plate spaced below the top of the casing and having a central opening therein, a cutter head having its upper end fitting revolubly in said opening, a flange on said cutter head below the plate and bearing on the under side thereof, a securing member screwed in said head and bearing against the upper side of the plate, a plunger extending 85 from said casing parallel to the axis of and adjacent said cutter head, and gearing connecting the plunger and cutter head to rotate the latter upon depression of the plunger, and spring means normally holding said plunger raised. 90

3. In a pencil sharpener, a casing, a partition plate spaced below the top of the casing and having a central opening therein, a cutter head having its upper end fitting revolubly in said opening, a flange on said cutter head below the plate and bearing on the under side thereof, a securing member screwed in said head and bearing against the upper side of the plate, a bevel gear surrounding and carried by the cutter head, a bearing depending from said plate, a shaft mounted in said bearing, a second bevel gear meshing with the first gear and fixed on the inner end of said shaft, a spur gear fixed on the outer end of said shaft, and a plunger 100 extending downwardly through the top of the casing and including a rack meshing with said pinion. 105

4. In a pencil sharpener, a casing, a partition plate spaced below the top of the casing and having a central opening therein, a cutter head having its upper end fitting revolubly in said opening, a flange on said cutter head below the plate and bearing on the under side thereof, a securing member screwed in said head and bearing against the upper side of the plate, a bevel gear surrounding and carried by the cutter head, a bearing depending from said plate, a shaft mounted in said bearing, a second bevel gear meshing 110

115

with the first gear and fixed on the inner end of said shaft, a spur gear fixed on the outer end of said shaft, a plunger extending downwardly through the top of the casing 5 and including a rack meshing with said pinion, and spring means normally holding said plunger raised.

5. In a pencil sharpener, a casing, a partition plate spaced below the top of the casing 10 and having a central opening therein, a cutter head having its upper end fitting revolvably in said opening, a flange on said cutter head below the plate and bearing on the under side thereof, a securing member screwed 15 in said head and bearing against the upper side of the plate, a worm gear surrounding and carried by the cutter head, a plunger extending downwardly through the top of the casing and including a multiple threaded 20 worm meshing with said gear, and means to guide said plunger and hold it against rotation.

6. In a pencil sharpener, a casing, a partition plate spaced below the top of the casing 25 and having a central opening therein, a cutter head having its upper end fitting revolvably in said opening, a flange on said cutter head below the plate and bearing on the under side thereof, a securing member screwed 30 in said head and bearing against the upper side of the plate, a worm gear surrounding and carried by the cutter head, a plunger extending downwardly through the top of the casing and including a multiple threaded 35 worm meshing with said gear, means to guide said plunger and hold it against rotation, and spring means normally holding said plunger raised.

7. In a pencil sharpener, a casing, a cutter 40 head rotatably mounted in said casing, a plunger extending from said casing, parallel to the axis of and adjacent said cutter head, gearing connecting the plunger and cutter head to rotate the latter upon depression of 45 the plunger, a stem extending downwardly from said cutter head and provided with a dust escape opening, and a guide seat on the bottom of the casing receiving and guiding the lower end of said stem.

50 8. In a pencil sharpener, a casing, a cutter head rotatably mounted in said casing, a plunger extending from said casing, parallel to the axis of and adjacent said cutter head, gearing connecting the plunger and 55 cutter head to rotate the latter upon depression of the plunger, spring means normally holding said plunger raised, a stem extending downwardly from said cutter head and provided with a dust escape opening, and a 60 guide seat on the bottom of the casing receiving and guiding the lower end of said stem.

In testimony whereof I affix my signature.
